UNITED STATES PATENT OFFICE

HARRY W. STERTZBACH, OF COLUMBUS, OHIO, ASSIGNOR TO THE BUCKEYE STEEL
CASTINGS COMPANY, OF COLUMBUS, OHIO

BOLSTER

Application filed January 11, 1927. Serial No. 160,434.

A car truck bolster is, in effect, a beam supported at its ends and carrying intermediate loads, the loads being assumed to act in two planes, one plane passing vertically through the longitudinal axis of the bolster and the other plane passing horizontally through said axis. The loads induce bending stresses in the bolster which are calculated on the commonly accepted theory of flexure that the intensity of fibre stress varies directly as the distance of the fibre from the neutral surface of the structure. The usual cross sectional form of a car truck bolster is that of a hollow rectangle or "box section," which provides considerable strength with economy of material, and it is evident that the maximum combined stresses occur at the corners. According to the mentioned theory, the stress along a horizontal transverse line of the bolster under vertical load is uniform but tests show the theoretical stress to be exceeded in the end portions of such line while at the centre the stress is less. It is the purpose of the present invention to provide a bolster which will be actually stronger with less weight than bolsters of the usual form, and to eliminate the corners on which, in the usual sections, the stresses from the two systems of loads combine to form the maximum. Structures embodying the invention are illustrated in the accompanying drawings and will be hereinafter fully set forth and particularly defined.

In the drawings, Figure 1 is a side elevation of one form of bolster embodying the invention;

Figure 2 is a transverse section on the line 2—2 of Fig. 1;

Figures 3, 4 and 5 are sections taken on the lines 3—3, 4—4 and 5—5, respectively, of Figure 1;

Figure 6 is a side elevation of a second embodiment of the invention;

Figures 7 and 8 are sections on the lines 7—7 and 8—8 respectively of Figure 6;

Figure 9 is a side elevation of an embodiment of the invention differing in details from the previously mentioned forms;

Figure 10 is a transverse section on the line 10—10 of Figure 9;

Figure 11 is a section on the line 11—11 of Figure 9;

Figure 12 is a view similar to Figure 10 but showing a variation in form;

Figure 13 is a section on the line 14—14 of Figure 14;

Figure 14 is a side elevation of an end portion of a bolster of another form.

The bolster 1 is tapered toward its ends from the centre and, in the form shown in Figures 1 to 5, has the usual flat top web 2 to accommodate attachments and bearings that are usually necessary on the upper side of the bolster. The bolster also has straight side portions 3 which at the ends of the bolster extend the full height thereof whereby to maintain the usual bearing area for the springs and have the proper engagement with the usual form of truck side frame. On the interior of the bolster, however, in its end portion, arcuate reinforcing ribs 4 are formed across the right angles defined by the side walls 3 and the bottom 5, and said angles are given a gradually increasing arcuate form on lines passing toward the center of the bolster and, at the region of the central internal brace 6, strict angularity of corners disappear and the sides and bottom are joined by true curves, as at 7. The radius of the curves in this form of the device, increases regularly toward the center of the bolster and, in the plane of Fig. 5, is equal to one-half the width of the bolster so that the lower or tension member becomes semi-cylindrical, the semi-cylindrical cross-sectional contour being continued to the center of the bolster on a gradually increasing radius, as will be understood on reference to Fig. 2.

The bolster 10, shown in Figures 6, 7 and 8, like the bolster shown in Figs. 1 to 5, tapers vertically from its center toward its ends. This form of bolster has the internal arcuate ribs 11 at the junctions of its side and bottom walls at its end portion 12 and also has the corresponding ribs 13 in its upper portion so that an elliptical cross-sectional contour is shown by the ribs. At a point inward from the end portion 12, the bolster is given an elliptical cross section as shown in Figure 8, the side portions 14 being nearly

semi-circular while the bottom 15 is flat at its center under the brace 16. To facilitate the mounting of accessories upon the bolster, flat-top projections 17 are formed on the sides of the top thereof so that the top or compression member of the bolster will present a flat surface, as shown in Figure 8. The curvilinear cross section of the tension and compression members of the bolster is continued toward the center of the bolster with the vertical axis of the ellipse gradually increasing until, near the center, the cross section more nearly approaches a circle, the center bearing surface 18 being formed in a manner similar to the projections 17.

In Figures 9, 10 and 11 is shown a bolster having a tension member 19 which is arcuate in cross section and has a curvature of substantially constant radius, from end to end, as shown in Figures 10 and 11. This bolster is of cast steel and at its outer end has a spring seat 20 cast integrally therewith, said seat presenting a flat surface to the upper ends of the truck springs and being reenforced by vertical webs 21 and 22 disposed respectively at the side edges of the seat and bolster end and at points near the center thereof. The structure shown in Figure 12 differs from that shown in Figures 10 and 11 in that the spring seat 23 is cast separately from the bolster and is interengaged with the bolster end by a lug and socket, shown at 24, the seat having a concave top web 25 to fit against the convex under side of the bolster end and extend to the top of the same.

In Figures 13 and 14 is illustrated a construction in which the bolster is of a built-up type, the tension member 26 having a transverse curvature which is of substantially constant radius throughout the length of the member. Flanges 27 extend along the top edges of the bolster and a top plate 28 is secured upon the flanges, said plate being dished and turned down at its outer end to fit within and be secured to the end of the tension member. The spring seat 29 is preferably a casting interengaged with the bolster end by a lug and socket, shown at 30, and having a concave top web seating the bolster end.

From the foregoing description, taken in connection with the accompanying drawings, it will be seen that I have provided a novel bolster which will possess all the advantages hereinbefore enumerated as desirable.

Having fully described my invention what I claim as new and desire to secure by Letters-Patent, is:

1. A car truck bolster having a tension member of arcuate cross section, and a compression member of inverted channel section from the central portion of the bolster outwardly to the ends of the bolster.

2. A car truck bolster having a tension member of arcuate cross section and a com-

pression member of inverted channel section from the central portion of the bolster outwardly, the radius of the former gradually uniformly increasing from the end portions of the bolster toward the center thereof, both the tension and the compression members extending outwardly to the ends of the bolster.

3. A car truck bolster in which the tension member has a cross section including a flat bottom and curved sides adjacent the end portions of the bolster and gradually uniformly merging into a semi-circle toward the center of the bolster, said tension member being coterminous with the bolster.

4. A car truck bolster having a tension member formed with a convex under side, and a flat spring seat adjacent to said convex under side, said bolster also having a compression member of inverted channel section from the central portion outwardly.

5. A car truck bolster having a tension member of arcuate cross section and a flat bottom spring seat adjacent the outer end of said member, said bolster having a compression member of inverted channel form from the central portion of the bolster outwardly.

In testimony whereof, I have signed this specification.

HARRY W. STERTZBACH.
